GOLF BALL RETRIEVER

John Kaanehe, 1516 Kam. 4th Road, Honolulu, Hawaii
Filed May 13, 1963, Ser. No. 280,765
2 Claims. (Cl. 294—19)

My invention relates generally to an accessory for a golf player and particularly to a golf ball retriever in the form of a club with a hollow head.

During a game of golf it becomes necessary to retrieve the golf balls many times during the course of play and often the ball comes to rest in places where the same cannot be retrieved by ordinary means. Accordingly an object of my invention is to provide a novel golf ball retriever, whereby a golf ball may be readily retrieved from normally inaccessible places.

Another object is to provide a golf ball retriever shaped and formed like a golf club with a hollow head and balanced so as to scoop up the ball with ease and efficiency into the confines of the hollow head of the retriever.

Another object is to provide a novel magazine type golf ball retriever whereby several golf balls may be successively scooped up and collected in the hollow body of the retriever.

Another object is to provide a novel golf ball retriever formed with a head portion simulating a golf club with a perforated bottom portion adapted to prevent water, sand or dirt from accumulating in the ball retriever head portion, whereby golf balls may be efficiently retrieved from under water, sand or loose dirt areas.

Still another object is to provide in a golf ball retriever formed with a hollow head portion having a side opening therein with a scoop-up edge or sill and a ball retainer means adapted to prevent the balls retrieved with each scoop-up motion of the retriever from rolling out of the head portion, until desired by the user.

Yet another object is to provide an economically fabricated ball retriever with a hollow head of lightweight and durable material shaped for example like a standard number one driver.

With the foregoing and other objects in view, my invention consists of certain novel features of construction, combination and arrangement of parts, as will now be more fully described and particularly defined in the appended claims.

In the drawing, wherein like parts are given like reference numerals and are thus identified throughout the following description:

FIGURE 1 is a perspective view of my club-type golf ball retriever taken of the front open ball retriever side thereof;

FIGURE 2 is a perspective view of the rear side of the ball retriever;

FIGURE 3 shows a golfer in the act of retrieving a golf ball with my novel ball retriever club; and

FIGURE 4 is a section view taken on the line 4—4 of FIGURE 1.

Referring in detail to the drawing and first with respect to FIGURE 1, the ball retriever club comprises a handle 10 secured to an angular extension or shank 11 in a socket, not shown, by reinforcing cord or gut windings 12, as is well-known in the manufacture of golf club drivers.

This extension or shank 11 is formed as a part of the hollow retriever head portion 13, which head portion is preferably made of plastic or fiber-wood although it may

2

be formed of suitable reinforced composition materials or light-weight metal.

The head portion 13 is in effect a shell having a rounded closed rear side 14, see FIGURE 2, and a front 5 relatively flat side 15 formed with a ball retriever opening 16 large enough to receive a golf ball and extending for the greater portion of the front side 15 of the head portion 13. The head portion is formed with a bottom portion 17, which bottom portion is preferably made 10 with a plurality of perforations 18.

The bottom portion 17 may be formed as an integral part of the shell-like head portion 13 and of the same material or it may be in the form of a separate perforated plate of different material, such as aluminum and be suitably combined with the shell of plastic material from which the head portion 13 may be made.

The bottom portion 17 in either event is formed with a ball scoop entrance sill 19 which curves inwardly toward the rear interior wall 20 of the hollow head portion

20 13. Slanting forwardly and upwardly at each end of the sill 19 are spaced side guide edges 21 and 22, which cooperate with the ball scoop sill 19 in facilitating the ball scoop-up action with each ball retrieve operation.

A ball retainer means, such as an elongated bar 24 25 is supported on the bottom portion 17 rearward of the ball scoop sill 19. The bar 24 may be of metal and extends longitudinally in the head portion 13 in substantially parallel relation to the sill 19. Also the bar 24 is tapered in cross section in the provision of a longitudinal 30 feathered edge 25 facing toward the longitudinal edge of the ball scoop sill 19. Thus, as a ball is retrieved by a swing of the club-like retriever to provide the scoop action thereof it rolls freely over the feathered edge of the bar 24 into the hollow head portion 13 and 35 is then retained against possible roll out by the non-feathered opposite side of the bar.

The hollow head portion 13 is made sufficiently large to receive and hold several golf balls at one time, for example, as many as five balls.

40

Manner of use

The manner in which the golf ball retriever is used is believed obvious from the foregoing description, for 45 example, golf balls are retrieved simply and easily by swinging the retriever toward a golf ball B to provide a scooping action, see FIGURE 3. Thus, as illustrated, by this action a golf ball is scooped up in an upward swinging motion of the retriever by the golfer to the left and with a naturally resulting tilting of the head portion 13 to the right so the ball will roll easily into the retriever over the feathered edge 25 of the sill 19.

Thus I have provided a novel natural swing actuated golf ball retriever, whereby no stooping to pick up balls 50 is required. Also, there is provided a retriever which may be used to retrieve golf balls from traps, such as water, sand and the like and places where the golf balls may be inaccessible without a ball retriever.

Without further description it is believed that the 55 advantages of the present invention over the prior art are apparent and while only one embodiment of the same is illustrated, it is to be expressly understood that the same is not limited thereto as various changes may be made in the combination and arrangement of the parts illustrated, as will now likely appear to others and those skilled in the art. For a definition of the scope or limits

of the invention, reference should be had to the appended claims.

What is claimed is:

1. Means for retrieving round objects comprising a handle, a club-shaped hollow head having top, bottom, front and rear sides, an opening in the front side thereof, said bottom being of perforated sheet material, an object engaging sill defining the lower edge of said opening, object retainer means mounted on the interior surface of the bottom of the head extending substantially parallel with respect to said sill, said last-named means having a feathered edge facing said sill, and spaced ball outwardly diverging guide means projecting forward of said sill, said sill being curved inwardly and being rearward of said guide means.

2. Means for retrieving round objects as described

in claim 1, wherein said object retainer means is an elongated bar.
